UNITED STATES PATENT OFFICE.

LOUIS SCHWINGROUBER, OF NEW YORK, N. Y.

SHOE-HORN.

Specification of Letters Patent No. 11,445, dated August 1, 1854.

To all whom it may concern:

Be it known that I, LOUIS SCHWINGROUBER, of the city, county, and State of New York, have invented and made a new and useful Improvement in Slips for Putting on Shoes; and I do hereby declare that the following is a full, clear, and exact description of the construction and operation of the same, reference being had to the annexed 10 drawing, making part of this specification, wherein—

Figures 1 and 2 are perspective views of the spring slip complete. Fig. 3, represents the same as opened ready for use. Figs. 4 and 5 represent the separate parts of the spring and slip. Figs. 6, 7, 8 and 9 represent the separate parts as they are cut out or stamped ready to be bent into the required shape by dies or similar means, and Fig. 20 10 shows the spring slip as in use.

The like marks of reference denote the same parts.

The nature of my said invention consists in the use of a spring clamp in combination 25 with the shoe slip by means of which the back of the shoe is securely held while being pulled onto the foot, and the metallic slip guides the heel down into place the same as an ordinary shoe horn or slip.

30 *a*, is a metallic plate. I prefer brass, stamped or cut out nearly in the shape of that shown in Fig. 6, the ears 3, 3, of which are turned up, and the part 1 formed concave as shown, and the part 2 forms a place 35 to take hold of. Through the ears 3 I insert a pin 4, that forms a fulcrum for a spring clamp *b*, the metal for which is cut

out in the shape shown in Fig. 9, or nearly so, and onto this clamp I rivet a hinge piece 5, which surrounds the wire 4, and forms 40 a fulcrum for said spring clamp. The end 7 of the spring clamp *b* is made concave to correspond with the part 1 of the slip *a*, and the end 6 is turned back and takes against the plate *a*, toward the fulcrum 4. When 45 this spring is to be used, the part 8 is to be pressed toward the part 2, which opens the jaws 7 and 1, into which the back part of the shoe is to be inserted, as seen in Fig. 10, and the spring allowed to clamp and hold 50 the shoe, while being drawn on, by taking hold of the part 2 of the slip *a*.

This improvement is more especially useful for the shoes of ladies and children than for any others.

I am aware that spring clamps of various kinds have been used, but I am not aware that a spring clamp *b*, formed in the manner herein shown has been used with the shoe slip *a*, as set forth therefore 60

What I desire to secure by Letters Patent is—

I claim the spring clamp *b*, with its concave holding jaw 7, in combination with the shoe slip *a*, the parts being constructed 65 and operating substantially as set forth.

In testimony whereof, I have hereunto set my signature this fifth day of July, one thousand eight hundred and fifty-four.

L. SCHWINGROUBER.
